[57] **CLAIM**

The ornamental design for a rake head, as shown.

DESCRIPTION

FIG. 1 is a perspective view of a rake head showing my new design;

FIG. 2 is a side elevational view thereof with the opposite side being a mirror image thereof;

FIG. 3 is a front elevational view thereof;

FIG. 4 is a top plan view thereof;

FIG. 5 is a bottom plan view thereof;

FIG. 6 is a rear elevational view thereof; and,

FIG. 7 is a sectional view thereof taken along line 7—7 of FIG. 3.

The broken line showing of a rake handle is for illustrative purposes only and forms no part of the claimed design.
